UNITED STATES PATENT OFFICE.

VICTOR G. GUSTAFSON, OF JOLIET, ILLINOIS.

AUTOMATIC BALANCING DEVICE.

977,523.

Specification of Letters Patent.

Patented Dec. 6, 1910.

Application filed July 28, 1909. Serial No. 510,081.

To all whom it may concern:

Be it known that I, VICTOR G. GUSTAFSON, a citizen of the United States, residing at Joliet, in the county of Will and State of Illinois, have invented a certain new and useful Improvement in Automatic Balancing Devices, of which the following is a specification.

My invention relates to automatic balancing devices especially for aeroplanes or flying machines but it is also applicable to submarine vessels.

The object of the invention is to provide means whereby the ship (which term will be employed to indicate vessels using either air or water as a suspension medium) will be automatically returned to a horizontal or other predetermined position.

A further object is to provide a device of this character which is automatic in its nature when left alone but which may be manually operated to alter its inclination from the horizontal. It will be understood that in a flying machine, for example, the machine will normally travel horizontally but when it is desired to make a landing it will be necessary to cause the forward extremity of the vessel to dip downward, and conversely when it is desired to rise to a higher altitude it will be necessary for the front of the vessel to be elevated. My device will normally keep the vessel horizontal but affords an opportunity to the operator to change the direction at will, and also to change the lateral inclination so that the vessel may be caused to circle to the right or left.

I accomplish my objects by the mechanism illustrated in the accompanying drawings, in which:

Figure 1 is a central vertical section of the device, Fig. 2 is a horizontal section thereof, taken on the line 2—2 Fig. 1, and Fig. 3 is a diagrammatic view showing the electrical connections.

It will be understood that the form of mechanism here shown is selected for illustrative purposes and that the invention may be embodied in a great variety of forms. The form selected, however, is advantageous, and is, therefore, preferred.

A vessel 1 of insulating material is filled with mercury to a proper level and is provided with a handle 2 by which the vessel may be tilted when desired. By preference

the vessel is provided with a glass cover 3 held in position by an annular screw cap 4 or other suitable means. In the sides of the vessel, preferably at four equidistant points, are arranged contact terminals 5, 6, 7 and 8. These terminals are all arranged at the same level and are provided with binding screws 9 or other suitable means for making electric connection between said terminals and the circuit conductors 10, 11, 12 and 13. A fifth contact terminal 15 is located in the handle 2 or in some other convenient portion of the vessel whereby it will be out of the way and yet permanently in contact with the mercury under all ordinary circumstances irrespective of the tilting of the vessel. Said terminal 15 is provided with a binding screw 16 or other suitable means for making electrical contact with the circuit conductor 17.

The vessel is yieldingly suspended in the ship in such manner that it will normally be held level or horizontal when the ship is level but may be manually moved from such position. The preferred means for thus suspending or mounting the device consists, as here shown, of four coiled springs 20, 21, 22 and 23 arranged equidistantly around the vessel and attached at one end to clips or lugs 24 on the vessel and at the other end to arms or brackets 25 rigidly secured to the frame of the ship. Any other suitable holding means may be substituted for the lugs or clips 24, and other resilient suspending means may be substituted for the coiled springs 20, but the aforesaid construction is suitable. More than four springs may be employed, if desired, but four are sufficient under ordinary conditions.

I will now explain the theory of my invention from the electrical standpoint, making special reference to the diagram, Fig. 3. Connected respectively to the conductors 10, 11, 12 and 13 are electrically controlled devices 30, 31, 32 and 33 which control the vanes, wings, rudders, propellers or other devices which govern the inclination of the ship. My invention has nothing to do with the specific construction of these controlling devices, it being sufficient for the present purpose to point out that four of such devices are sufficient to directly or indirectly produce a controlling effect at any one of the four cardinal points of the compass, or at any two of them. These devices may be

multiplied in number as may also the number of the leveling terminals 5, 6, 7, 8; but the theory in each case will remain the same. Electrical energy for operating said electrical controlled controlling devices is furnished by a battery 35 or other suitable source. For convenience this is connected between the conductor 17 and the conductors 36, 37, 38 and 39 leading respectively to the controlling devices 30, 31, 32 and 33.

10 In operation, the vessel 1 is fitted with mercury to such a height that when said vessel is level the surface of the mercury will be just below and out of contact with the leveling terminals 5, 6, 7 and 8. Under such circumstances the circuits in the apparatus will be open, and consequently no current will be impressed upon any of the electrically operated controlling devices 30, 31, 32 or 33. Under these, the normal conditions, the ship will tend to maintain its horizontal position. If, now, the ship, for any reason, tilts from the normal position some one or some two of the terminals 5, 6, 7, 8 will be 20 come submerged in the mercury and thus establish a circuit through the corresponding one or two of the devices 30, 31, 32 or 33. This will put in operation the proper mechanism to right the ship, that is, return it to 25 horizontal or normal position. As soon as the ship has been righted the circuits will again open and remain open during normal conditions. If the operator desires to produce any tilting of the ship he merely applies pressure to the handle 2 in such manner as to cause the submergence in the mercury of the proper one or pair of terminals.

Although it is preferable that in operation the mercury containing vessel shall be 30 filled only to a point beneath the terminals 5, 6, 7 and 8, it is obvious that the vessel may be filled to a level slightly above said terminals. In such case, under normal conditions, the circuits will be broken only 35 when the containing vessel is tilted sufficiently to uncover one or more of said terminals. Such method of operation, however, has the disadvantage of wasting the battery or other source of electrical energy, 40 and is, therefore, not so good as the method first described.

Ordinarily it will be desirable to prevent surging of the mercury or other liquid conductor in the vessel, and although mechanical baffles may be employed, I prefer to accomplish the purpose by filling the space above the mercury with a fluid or semi-fluid material which is but an imperfect conductor of electricity.

50 Having thus described my invention, what I claim as new and desire to secure by Letters Patent, is:

1. In a device of the class described, the combination of a vessel of insulating material adapted to contain mercury up to a cer-

tain level, a terminal adapted to contact the mercury far below its surface, a plurality of terminals mounted upon said vessel at the same height and at about the level of the mercury, and a removable transparent cover 70 for preventing the escape of the contents of the vessel.

2. In a device of the class described the combination of a vessel adapted to contain a fluid conductor, a terminal adapted to remain in contact with said fluid conductor, a plurality of terminals mounted upon said vessel at substantially the same level whereby they are immersed or uncovered depending upon the tilt of the vessel, and means for 75 yieldingly supporting said vessel.

3. In a device of the class described the combination of a vessel adapted to contain a fluid conductor, a terminal adapted to remain in contact with said fluid conductor, a 85 plurality of terminals mounted upon said vessel at substantially the same level whereby they are immersed or uncovered depending upon the tilt of the vessel, means for yieldingly holding said vessel level and 90 means for tilting said vessel against the force of said yieldingly holding means.

4. In a device of the class described, the combination of a vessel adapted to contain a fluid conductor, a terminal adapted to remain in contact with said fluid conductor, a plurality of terminals mounted upon said vessel at substantially the same level whereby they are immersed or uncovered depending upon the tilt of the vessel, at least four 100 springs equally distributed around said vessel for yieldingly supporting the same, and means for tilting said vessel in opposition to said springs.

5. In a device of the class described, the 105 combination of a vessel adapted to contain a fluid conductor, a terminal adapted to remain in contact with said fluid conductor, a plurality of terminals mounted upon said vessel at substantially the same level whereby they are immersed or uncovered depending upon the tilt of the vessel, means for yieldingly holding said vessel level and a 110 handle on said vessel for manually tilting it.

6. In a device of the class described, the 115 combination of a vessel adapted to contain a fluid conductor, means for electrically energizing said fluid conductor and four terminals arranged equidistantly around said vessel at substantially the same level, whereby they are immersed or uncovered, depending upon the tilt of the vessel, it being possible for any two adjacent terminals to be 120 uncovered while the remaining two are covered and vice versa.

7. In a device of the class described, the combination of a vessel adapted to contain a fluid conductor, means for electrically energizing said fluid conductor, four terminals arranged equidistantly around said vessel at 125 130

substantially the same level, whereby they are immersed or uncovered, depending upon the tilt of the vessel, it being possible for any two adjacent terminals to be uncovered while 5 the remaining two are covered and vice versa, and means for manually controlling the tilt of said vessel.

In witness whereof, I have hereunto subscribed my name in the presence of two witnesses.

VICTOR G. GUSTAFSON.
